(57) **CLAIM**

The ornamental design for a cap for rear wiper motor, as shown and described.

DESCRIPTION

FIG. 1 is a perspective view of a cap for rear wiper motor. FIG. 2 is a front elevation view thereof. A rear elevation view, a left side elevation view and a right side elevation view are identical with the front elevation view. FIG. 3 is a top plan view thereof. FIG. 4 is a bottom plan view thereof.

FIG. 5 is a cross-sectional view thereof taken along line 5-5 in FIG. 2; and, FIG. 6 is a referential view showing use thereof. In the drawings, the broken lines in FIG. 6 depict a vehicle and form no part of the claimed design.
